VENDING MACHINE CABINET

Lincoln M. Keefe, New York, N. Y.

Application July 31, 1953, Serial No. 26,206

Term of patent 14 years

(Cl. D52—3)

FIG. 4

FIG. 1

FIG. 2

FIG. 3

Figure 1 is a front elevation of a vending machine cabinet showing my new design;

Figure 2 is a side elevation of the vending machine cabinet shown in Figure 1;

Figure 3 is an elevation of the vending machine cabinet of Figure 1 as seen from the back thereof; and

Figure 4 is a view of the vending machine cabinet of Figure 1 as seen from above.

I claim:

The ornamental design for a vending machine cabinet, as shown.
